MANUFACTURING COMPANY, OF MILFORD, CONNECTICUT, A CORPORATION
OF CONNECTICUT.

WIND-SHIELD HINGE-JOINT.

1,159,506.

Specification of Letters Patent.

Patented Nov. 9, 1915.

Application filed September 19, 1914. Serial No. 862,474.

To all whom it may concern:

Be it known that I, PETER N. LANDINE, a citizen of the United States, residing at Milford, New Haven county, State of Connecticut, have invented certain new and useful improvements in Wind-Shield Hinge-Joints, of which the following is a full, clear, and exact description.

This invention relates to hinge joints for wind shields and aims to provide a simple and efficient device of this character embodying new and improved features of construction.

The invention is described in detail in the following specification taken in connection with the accompanying drawings forming part thereof, and in which—

Figure 1 is a fragmentary view in front elevation of a wind shield hinge joint constructed in accordance with the present invention. Fig. 2 is a transverse vertical section on the line 2—2 of Fig. 1. Fig. 3 is a detail perspective view of the supporting bracket and fixed socket portion. Fig. 4 is a detail of the movable socket portion, and Fig. 5 is a detail of the hub portion of the fixture.

Referring to the drawings by numerals: 1 indicates a bracket-plate shaped for application to the underside of the roof or other hanging part of a motor car body. This bracket-plate is formed integral with and part of one of two separable parts forming the hinge joint, the main body of which part comprises a central disk-like portion 2 having its inner face cut away at one side to form a substantially semi-circular wall 3 and a solid back or base 4. Above the upper terminus of the wall and below the bracket-plate 1, this inner face is recessed laterally to form a socket or journal bearing 5 extending to a point below the base 4, forming a step bearing 6 for the inner end of the hinge pin of a second substantially semi-circular but movable clamping portion or wall forming the other half of the socket member of the hinge joint, the semi-circular wall 3 forming the fixed and first half portion of this socket member. From the lower terminus of the disk portion 2, the body is reduced in size to form a shank or standard portion 7, which may be suitably formed to receive the upper end of the usual support-

ing standard attached, for instance, to the upper edge of the dash. From the lower terminus of the semi-circular portion 3 the face of the disk portion is further cut away to provide an abutment wall 8, having therein a threaded socket 9 for the end of a clamping screw. Between the socket 5 and the upper extremity of the wall 3, a second abutment wall 10 is formed and the adjacent side of the socket 5 is cut away at 5^a from the base 4 upwardly.

As above stated, the semi-circular wall 3 forms the fixed half portion of a sectional socket member. The movable and complementary portion of this socket member comprises a clamping piece 11 having at its upper end a hinge pin or stud 12 shaped to be seated in the socket 5 of the fixed section by a lateral sliding movement. The lower end of this pin extends beyond and is offset from the body of the movable section as at 13, this offset portion seating in the step bearing 6 of the socket portion, which bearing centers the pin or stud therein.

Adjacent and below the pin or stud, this movable socket portion is provided with an abutment wall 14, shaped and designed to engage the upper abutment wall 10 of the fixed socket section, the lower edge of this wall 14 forming the upper end of a semi-circular portion 15, complementary to the semi-circular wall 3. At the lower extremity of this semi-circular portion 15 is a foot or flange 16 complementary to the abutment wall 8 and having therein an alined bore 17.

The movable and removable section 11 of the socket member is applied to the fixed section by inserting the hinge pin or stud 12 into the journal bearing 5 and moving the same laterally of the fixed section and axially of the socket to seat the offset 13 in the step bearing 6. When this movable section is swung toward the fixed section, the walls 10—14 and 8—16 will abut, the two sections forming a substantially semi-circular socket or opening. The wall of the fixed section 10 above and adjacent the socket portion 5 is cut away as at 18 to permit the movable section 11 to be swung outwardly so as to open the socket to receive the hub portion of the hinge joint. This hub portion carries a movable wind shield section and comprises a cylindrical hub portion 19 having an annular groove 20 therein intermediate its

ends. At its outer extremity the hub 19 is formed with a concentric bearing flange 21 formed integral with the hub and having attached thereto and preferably integral therewith, a corner portion 22 of the frame of the wind shield section. The hub portion 19 is of a diameter equal to the diameter of a socket formed by the fixed semi-circular wall 3 of the socket. The movable section 11 of the socket has its semi-circular portion 15 formed on an arc slightly less than the arc of the portion 3 and of the hub, so that when the hub is inserted within the socket portion and the movable portion 11 of the socket closed, there will be a frictional grip on the hub portion 19. In order to hold the hub portion 19 in adjusted position within the socket member, a thumb screw 23 is provided, which thumb screw is inserted through the bore 17 in the movable section 11 and takes into the threaded bore 9 of the fixed socket section. With the hub portion inserted and the movable socket section closed, the thumb screw may be turned up to force the movable section against the hub to hold the latter firmly in adjusted position within the socket. The bearing flange 21 of the hub member, in this position of the parts, will rest against the outer faces of the semi-circular socket sections 3 and 15 and will have a bearing thereon, taking part of the supporting load of the wind shield from the hub portion 19 in the event of any looseness from wear or sagging, as well as covering the socket opening from view. The hub is centered in its socket by means of a key or pin 24 extending radially inward from the semi-circular wall 3 and taking in the annular groove 20 of the hub. It will be evident that the hub with its wind shield section may be removed bodily by loosening the clamping screw 23 and swinging the movable socket section outwardly.

It will be seen that the hinge joint described presents a neat and attractive appearance and unbroken lines toward the outside and with but a minimum portion of the hinging parts exposed. By having a removable portion for the socket member, the wind shield section may be applied at any time, minimizing the danger of shield breakage during manufacture or repair of the car to which it is applied.

What I claim is:

1. A hinge joint embodying a socket member and a hub member arranged to be adjustably supported thereby, said socket member comprising a solid base with an integral substantially semi-circular wall and with an adjacent hinge socket therein and with a complemental substantially semi-circular swinging wall portion journaled in said hinge socket, and seated over said base, the said hub member having a hub portion arranged to seat between said walls and having a

flange arranged to bear upon the outer edges thereof, with means for holding said walls in clamping engagement with said hub.

2. A hinge joint embodying a socket member and a hub member arranged to be adjustably supported thereby, said socket member comprising a standard having an enlarged portion recessed to provide a solid base with an integral substantially semi-circular wall and with an adjacent hinge socket therein and with a complemental substantially semi-circular swinging wall portion journaled in said hinge socket and seated over said base, the said hub member having a hub portion arranged to seat between said walls and having a flange arranged to bear upon the outer edges thereof, with means for holding said walls in clamping engagement with said hub.

3. A hinge joint embodying a socket member and a hub member arranged to be adjustably supported thereby, said socket member comprising a solid base with an integral substantially semi-circular wall and with an adjacent hinge socket therein and with a complemental substantially semi-circular swinging wall portion journaled in said hinge socket and seated over said base, the said hub member having a hub portion arranged to seat between said walls and provided with an annular groove therein and also having a flange arranged to bear upon the outer edges thereof, with means for holding said walls in clamping engagement with said hub, one of said walls having a member arranged to project into said hub groove to prevent bodily removal thereof axially from the socket.

4. A hinge joint embodying a socket member and a hub member arranged to be adjustably supported thereby, said socket member comprising a standard having an enlarged portion recessed to provide a solid base, with an integral substantially semi-circular wall and with an adjacent hinge socket therein and with a complemental substantially semi-circular swinging wall portion journaled in said hinge socket, and seated over said base, the said hub member having a hub portion arranged to seat between said walls and provided with an annular groove therein and also having a flange arranged to bear upon the outer edges thereof, with means for holding said walls in frictional clamping engagement with said hub, one of said walls having a member arranged to project into said hub groove to prevent bodily removal thereof axially from the socket.

5. A hinge joint embodying a socket member and a hub member arranged to be adjustably supported thereby, said socket member comprising a solid base with an integral substantially semi-circular wall and with an adjacent hinge socket therein extending to a

point below said base and with a complementary substantially semi-circular swinging wall portion having a hinge pin with an axially offset end and journaled in said hinge socket and seated over said base, the said hub member having a hub portion arranged to seat between said walls and having a flange ar-

ranged to bear upon the outer edges thereof, with means for holding said walls in clamping engagement with said hub.
